Inventor:

Harry DAW.
By John Pitt Bayley,
attorney.

UNITED STATES PATENT OFFICE.

HARRY DAW, OF HIGH WYCOMBE, ENGLAND.

PROTECTOR FOR WRIST-WATCHES.

1,249,906.

Specification of Letters Patent. Patented Dec. 11, 1917.

Application filed January 17, 1916. Serial No. 72,542.

To all whom it may concern:

Be it known that I, HARRY DAW, a subject of the King of Great Britain, residing at 7 Oxford street, High Wycombe, in the county of Buckinghamshire, in England, have invented a new and useful Improved Protector for Wrist-Watches, of which the following is a specification.

The invention relates to an improved pro-
10 tector for wrist watches.

In the accompanying drawings Figure 1 is a top or edge view of the disk, Fig. 2 is a front elevation or face view of the disk, and Fig. 3 is a back elevation of the disk before
15 the laths are bent to the required angle with the disk body.

My invention consists of a metal disk 1, suitably domed to cover a watch, with a series of bars or laths *a* cut across the center
20 with perforations *b*, each bar *a* to be set at

an angle after the manner of the laths of a Venetian blind, so that by tilting the watch a view of the dial and hands is obtained. The metal disk *a* is to be held in position by a loop *c* or slot on each side thereof,
25 through which the strap of the watch would pass.

I claim:

A metal disk suitably domed to cover a watch, having a series of slits cut across the center forming bars or laths, said bars being bent at an angle with the disk body, so that by tilting the watch a view of the dial and hands is obtained, the said disk being provided with loops through which the strap
30 35 of the watch passes.

HARRY DAW.
